[57] **CLAIM**

The ornamental design for the throttle body, as shown and described.

DESCRIPTION

FIG. 1 is a top plan view thereof;

FIG. 2 is a front elevational view thereof, the rear elevational view being the same as said front elevational view;

FIG. 3 is a bottom plan view thereof;

FIG. 4 is a right side elevational view thereof, the left side elevational view being the same as the right side elevational view; and,

FIG. 5 is an enlarged perspective view of a throttle body showing my new design.
